UNITED STATES PATENT OFFICE.

HENRY BERRY, OF HUNTINGTON, CONNECTICUT, ASSIGNOR TO THE DERBY SILVER COMPANY, OF SAME PLACE.

DESIGN FOR A HANDLE FOR COMBS.

SPECIFICATION forming part of Design No. 20,012, dated July 15, 1890.

Application filed June 16, 1890. Serial No. 355,656. Term of patent 7 years.

To all whom it may concern:

Be it known that I, HENRY BERRY, a citizen of the United States, residing in the township of Huntington, (Shelton,) and State of Connecticut, have invented and produced a new and original Design for a Handle for Combs, Brushes, and other Articles, of which the following is a specification, reference being had to the accompanying drawing, forming part thereof, and which shows a plan view of a handle for combs, brushes, and other articles ornamented in accordance with my design.

The leading features of my design consist in the form or outline of the handle and the ornamental figures thereon, as shown in the drawing, and more particularly referred to hereinafter.

The upper portion of the handle (lettered A) is convex on its opposite edges, and at said points bears the fluted scrolls B C, developed

from the convolved figures D D and inclosing the spray of leaves and flowers E, which occupy the upper central field of the handle. Below the fluted scrolls B C the edges of the handle contain the convex curves a, ornamented with conventionalized leaves b and inclosing the conventionalized foliate scroll F, below which the handle bears the spray of leaves and flowers G and terminates in the convolved arm H, as shown in the drawing.

What I claim as my invention, and desire to secure by Letters Patent, is—

The design for a handle for combs and other articles, substantially as shown and described. 35

In witness whereof I hereunto affix my signature, at Shelton, Connecticut, this 13th day of June, 1890.

HENRY BERRY.

In presence of—

WESLEY L. CLARK,
M. A. WHITE.
